VALVULAR FILLER SPOUT

Walter T. Eitzel, Philadelphia, Pa.

Application May 24, 1933, Serial No. 672,695

14 Claims. (Cl. 226—127)

This invention relates to filler spouts for dispensing fluids, and in particular, to improvements in valvular filler spouts.

The type of valvular spout hereunder considered is especially applicable for dispensing volatile liquids as gasoline at filling stations and the like, where it is difficult, tedious, and oftentimes, particularly at night, impossible to accurately gauge the height of liquid column in a tank or container being filled.

Then too, since the maximum return on the investment often requires a minimum number of operators, and since business during the day and week comes more or less in "spurts", each operator is often so "pushed" that he must employ every second of his time, and in the "rush", very frequently, when told to "fill it up", runs the tank over. This latter condition not only antagonizes the driver of a recently polished car, and adds to the fire hazards, but also wastes the fluid being dispensed to the prejudice of either the gasoline, oil, or liquid dealer, or the car owner, himself.

The attendant or operator should have some form of dispensing mechanism that enables him to positively bring the level of fluid in a container to a desired height without the necessity of constant inspection and attention; and that will even enable him to take care of other duties while fluid or liquid is being dispensed, with the assurance that no loss, damage, or difficulty will occur in his absence.

Although there have been devised forms of filling nozzles or spouts for the above-mentioned purposes, to my knowledge, none of them have come into general usage. Some have such a needless complexity of parts that efficient and consistent sensitiveness of operation is impossible; some are so crude that satisfactory operation is impossible; others require such a lengthy snout that the space limitations set by the majority of automobile manufacturers in the location of the tap, bung, or filler hole are clearly violated; others make no provision for varying the depth to which the tank, vessel, or receptacle may be filled; still others require a constant motivation in order that the shut-off valve may operate at the proper instant, and, it has been an object of my invention to provide an improved form of valve that will overcome disadvantages of present devices.

Another object of my invention has been to devise a nozzle for dispensing liquids that is easy to manipulate and handle.

Another object of my invention has been the

provision of a nozzle valve that is positive yet sensitive in operation.

A further object of my invention has been to provide an efficient, effective, simple, and inexpensive form of valvular nozzle or filler spout.

These and many other objects of my invention will appear to those skilled in the art from the following description taken in conjunction with the drawing, in which:

Fig. 1 is a vertical elevational view, partially in section, of an illustrative embodiment of my invention;

Figs. 2 and 3 are perspective showings of certain details;

Fig. 4 is a vertical view in elevation of another detail; and

Fig. 5 is a perspective showing of a modified form of detail.

Although I have illustrated my invention as embodied in several forms, it will be apparent to those skilled in the art, that its scope is in no sense limited to such forms.

In the drawing, the numeral 10 is representative of the valvular nozzle or spout as a whole. The nozzle 10 includes an inlet chamber, pipe 25 or tube 11 in which a valve 16 is inclinedly disposed, an outlet or discharge chamber, pipe, or tube 12 having a float chamber 12a therein, and a mount and guard system 25—26—31 having an operating mechanism mounted thereon.

As shown, the inlet member 11 is divided into two compartments by an inclined partition member 14 that has a fluid passage or port 15 therein whose edges may be tapered to better form a valve seat. In order that the flow of fluid through the partition 14 may be limited or controlled, a suitable overhead or upwardly opening valve 16 has been provided. The valve 16 may be of annular form having a cone-shaped or converging bottom portion, an upper portion of hollow or sleeve construction; and, the bottom portion is grooved for receiving a seat washer 18 of some suitable material such as fiber, leather, or soft metal. The upper portion of the valve 16 has a cup-like form to receive a spiral positioning spring 19 therein, and is slidably disposed within and sealed from fluid in the chamber 11 by an inspection cap 22 that is removably secured within upwardly projecting threaded portions 21 of the inlet member 11. The inspection plug 22 may be provided with an ordinary form of wrench-flat in order that it may be tightly secured in locking position as well as readily removed thereafter. It will be noted that the spring 19 is protected from the

fluid by the plunger-like fit between the cup-like valve sleeve and the inside of the cap 22.

The lower portion of the valve 16 has a stem 17 extending downwardly therefrom. As seen, the member 11 is provided with a downwardly inclined positioning extension through which the valve stem 17 extends. In order to provide a fluid tight seal, I have inserted suitable packing 23 between the extension of the member 11 and the valve stem 17. The packing 23 is adjustably held in place by a slideable packing sleeve 23a; the latter in turn, is adjustably held in a given position by a threaded packing cap 23b.

The right-hand or open end of the inlet tube 11 is internally threaded to receive the ordinary form of filler tube or hose (not shown); but the other end 13 of the inlet tube 11 and the upper end of the discharge tube 12 may be threaded and connected to form a unitary and continuous member. Although, for the purposes of inspection and repair, a threaded or removable connection is preferable, any form or fit may be employed. If desired, the discharge pipe 12 may be provided with a short length of flexible hose. By devising two independently separate and parallel chambers or passages in the discharge spout 12, I have been able to not only eliminate any dead end space, and to materially lessen the length of the spout, but in addition, to accurately gauge the amount of gasoline or other fluid fed into the tank being filled and to carry out such gauging practice between wide limits or between a wide scale or range.

The inner or float chamber 12a is sealed from the inside wall of the discharge spout 12, in order that fluid can enter therein from the bottom only. A float 38, itself of cylindrical form and of floatable construction such as of thin metal, is disposed within the chamber 12a to gauge or indicate the liquid level of the tank being filled and thus to indirectly control the operation of the valve 16.

The outer wall of the discharge pipe 12 may be suitably calibrated for different size tanks and in addition, may be calibrated to different liquid levels, irrespective of actual liquid measure.

To aid in this, in the embodiment of Fig. 4, I have shown a longitudinal strip 52 which is provided with a series of notches, flares, or teeth adapted to rest upon the top edge of the filler hole of a tank and restrict the penetration depth of the discharge spout 12. The notches may be spaced to conform to certain desired variations of liquid levels to be attained. The strip is rigidly secured to and forms an integral part of the outer wall of the spout 12, and, since the nozzle is generally inserted at an angle into the tank to be filled, the notches of the strip 52 will function even in an extremely large size filler hole.

In order that the valve operating mechanism may be compactly, securely, and effectively mounted in a proper position, I have furnished a mount frame and guard system designated by the numerals 25, 26, and 31. The inlet member 11, and the outlet member 12 are each respectively provided with mounting lugs extending from the outer walls thereof and adjacent their point of juncture, the member 11 is provided with a lug 25 projecting therefrom. This frame or guard system is mounted to extend downwardly and inwardly from the inlet member 11 and sidewise and inwardly from the outlet member 12, adjacent the angular bend therebetween.

75 Suitable side enclosing plates 27, one of which

is shown, may be mounted over the mount and guard system in order to suitably protect the operating mechanism. In the drawing of Figure 1, the left-hand plate has been removed showing the mounting screw holes while only the right-hand plate is in place.

In the embodiments of my invention shown, the operating mechanism or lever system includes resetting mechanism, trip mechanism, lost-motion mechanism, balance mechanism, and float means.

Since the spring 19 normally holds the valve 16 in a closed position, it follows that the operating mechanism must compress the spring during normal periods of fluid flow and must release it when the desired height of liquid in the container has been reached. In order to attain this result, a lever system has been devised which includes a valve operating or lever guide 24 having a practically straight portion upon which is formed a valve-stem seat (see Fig. 1), the end of which is bifurcated and pivotally secured by pivot means to the centrally extending lug 25.

The other substantial half or the extending portion of the guide lever 24 is upwardly concaved or curved to cooperate with the reset mechanism which includes a reset cam 28 rigidly secured on a pivot shaft 29 which in turn, is pivotally supported between bifurcated ears 30 extending upwardly from the upper surface of the partition arm 31.

In order that the operator may partially rotate the cam 28 and raise the valve guide lever against the resiliency of the spring 19 into a valve opening position, the right end of the shaft 29 (from the attendant's normal position) extends through the right-hand cover 27 a distance sufficient to permit a push lever 32 (see Fig. 3) to be secured thereto.

As seen, the cam 28 has two oppositely projecting faces, the upper of which may be rounded to smoothly lift the curved portion of the guide lever 24, the lower end of which is abrupt or pointed, in order that during the period when the cam is in a raised position, the lower end will extend downwardly through a slot cut centrally through the longitudinal partition member 31 and cooperate with and reach into a complementary slot 35 cut in a catch lever 33. The catch lever 33 is pivotally secured within the upper portions of the bifurcations of a downwardly extending lever-mounting lug 34. The other, or the extending end portion of the catch lever 33 is connected to a "lost motion" link 40, which in turn, is connected to a float controlled lever 39.

As seen, the upper end of the connecting arm 40 is longitudinally slotted at 41 in order that it may be slidably pivoted in a "lost motion" manner to the catch lever 33. The links or levers 33, 40, and 39 may be pivotally connected together by cotter or any suitable form of pivot pins. The effective length of the slot 41 substantially represents the distance of slide of the connecting lever 39, and thus, represents the distance of rise of the lever 39 before the lower end of the slot 41 abuts the connecting pin of the catch lever 33 and pushes the end of such catch lever upwardly about its pivot point to release the cam 28. The slot 41 may be lengthened or shortened, if desired, in order that any degree of lost motion between the travel of the link 40 and the operation of the tripping mechanism may be attained.

Now, referring particularly to the embodiment

of Figure 1, it is seen that the lever 39 is pivotally connected to the outer portions of the bifurcated mounting lug 34 and has an arm extending through a slot in the float chamber 12a; this arm is suitably drilled out to receive a wire connector 38 which is suspended in pendulum-like fashion therefrom and supporting a float 36.

In order that the valve 16 may be snapped shut by the operator at any time, regardless of the amount of fluid in the tank being filled, a trip mechanism including a lever 46 is pivotally mounted to extend through the frame member 26. The lever 46 has an upwardly curved and extending dog 47 adapted to cooperate with the short end of lever 33. This dog portion 47 is normally held out of abutment with the lever 33 by the off-balancing weight of the long and upwardly curved trip arm portion of lever 46.

To set the valve 16 to an open from a closed position, the knob 32 on the end of the reset cam shaft 29 is pushed, and thus, turned or partially rotated in a forward or clockwise direction until the lower face portion of the cam 28 slides into a "set" or locked relation with the slot 35 of the catch lever 33; this rotation causes the other end of the cam 28 to raise the guide lever 24 and the valve rod or stem 17 against the resiliency of the spring 19. Thus, the spring 19, by reason of its compressive force, aids in holding the cam 28 and the catch lever 33 in a cooperating relationship until they are released by other mechanism. Now, the filler nozzle 10 will permit a flow of fluid in the direction indicated by the arrows through the inlet pipe 11, past the valve 16 and out through the discharge pipe 12.

As the flow of liquid is initiated and fluid rushes into the tank or container, the float 36 will slowly rise until the lower end of the slot 41 in the connecting or "lost motion" arm 40 contacts with the pivot pin of the catch lever 33, after which the extending end of the catch lever 33 is raised and the cam 28 is snapped out of complementary relationship with respect to the slot therein by the force of the compression spring 19. Simultaneously, of course, the valve 16 is snapped shut.

As shown, the float chamber 12a is separately formed and is rigidly secured to a portion of the inside wall of the discharge or outlet chamber 12. The float 36 and the valve 16, have a diameter somewhat smaller than that of their respective chambers, and annular ribs 36a and 16a, respectively, act as liquid seals and as slide surfaces. It should also be noted that a seat washer 18 of conic form is held in place on valve 16 by a screw nut 18a.

In Fig. 3, I have shown a thumb or push lever 32, partially enclosed by a slotted cap 21a that constitutes an extension of the right-hand cover plate 21. The cap 21a aids in the manipulation of the push lever 32, since the operator can grip it with his hand while operating the lever with his thumb or finger.

In order to control the quantity rate or amount of fluid flow past the valve 16, I have provided the seat portion of the guide lever 24 with a slot and have journaled a cam shaft 41a upon the walls adjacent such slot and between those walls and suitable strips 42. As shown, the cam 40a (or 40a') is mounted in the slot and is rigidly secured to shaft 41a; at its extending end the shaft is provided with a hand lever 43a, which, when turned vertically upward, rotates cam 40a (or 40a') until its lower, or in the case of cam 40a, its flat face, comes in contact with the end

of the valve stem 17; when turned vertically downward, it exposes its higher or raised face to stem 17. In this manner the operative effectiveness of the guide lever 24 may be varied before and after the operating cam 28 has been set, in the case of the smooth face cam 40a' of Fig. 5, and before it has been set, in the case of the abrupt face cam 40a of Fig. 4 or 5.

In Figs. 1 and 5, the flow rate control cam 40a (or 40a') is shown in a "fast" position, for the valve stem 17 is raised the maximum height from its seat against the resiliency of the spring 19 (see Fig. 1) when the guide lever 24 is set; the depressed or lower face of flow rate cam 40a is shown in position for "slow" flow in Fig. 2. Thus, it appears that the rate control mechanism modifies the effectiveness of the guide lever 24 with reference to the opening of valve 16, and with reference to the consequent fluid flow therethrough.

From the above explanation, it will appear that the cam 40a (or the cam 40a') is positioned between the operating system and the valvular means in such manner that the effective travel of the parts of such system may be varied. That is, the cam means is provided in order that the degree of opening of the valvular means, and thus, the amount or quantity rate of fluid flow therethrough may be controlled independently of such system. Although such an operating lever as 24 or such a cam as 28 will actually be moved to the same position when the valvular means is to be opened, yet the effective distance is not actually the same when considered from the standpoint of the valvular means 16 or its associated stem 17. The diameter of the cam 40a (or 40a') will thus govern the height or distance to which the valve 16 is raised from its seat 14.

The catch lever 33 is provided with somewhat of an angular bend in the substantial center of its longer extending end in view of the fact that its other extending end, beyond the slot 35, is provided with a curved shoulder adapted to be tripped by the upwardly extending dog portion 47, and also, in view of the fact that the lever 39 is pivotally mounted at one end in a bifurcated lug 34a extending inwardly from the side of mount 26. As seen in Fig. 1, trip lever 46 is off-balanced in such a manner that its dog portion 47 is normally raised out of abutment with the shoulder of lever 33 and is operated or tripped by an upward pull of the finger of the operator on its handle portion. Dog 47 moves downwardly and forwardly to release catch lever 33, and the face end of cam 28 moves forwardly (to the left in Fig. 1) and upwardly to release guide lever 24. When the valvular mechanism is "set", the levers 33 and 39 have a certain relative relationship with respect to each other.

As the flow of fluid is initiated and it rushes into the container, the float 36 will slowly rise until the lower end of the slot 41 in the connecting or lost-motion link or arm 40 contacts with the pivot pin of the catch lever 33, after which, the extending end of the catch lever 33 is raised and the cam 28 is snapped out of a complementary relationship with respect to the slot therein by the force of the compression spring located in the inlet chamber 11. Simultaneously, of course, the valve is snapped shut.

In the embodiment of my invention herein illustrated, the lever systems are sensitively operable and will automatically close or trip the valve mechanism when the nozzle is tipped too far to the left, right, front, and/or rear by reason

of the consequent change in their centers of gravity. This is an additional safety feature, in that fluid flow is immediately shut off, if and when the nozzle is accidentally pulled or knocked 5 out of the filler hole of a tank or the like.

Although I have shown particular embodiments of my invention for the purpose of illustration, yet many modifications, substitutions, omissions, and the like may be made without departing from the spirit and scope of my invention. 10

What I claim as new and desire to secure by Letters Patent is:

1. In a filler spout, the combination of valvular means disposed therein for controlling fluid flow therethrough, an operating member for moving said valvular means to an open position, and means mounted on the spout for controlling the movement of said operating member and 15 regulating the quantity rate of fluid flow, said means being operable from the outside of the spout, so that the movement of said operating member may be controlled thereby for each operation thereof.
2. In a filler spout, the combination of valvular means disposed therein for controlling fluid flow therethrough, an operating member for moving said valvular means to an open position, and a lever means operably mounted upon the 20 spout for controlling the movement of said operating member and regulating the quantity rate of fluid flow.
3. In a filler spout, the combination of valvular means disposed therein for controlling fluid flow therethrough, an operating member for moving said valvular means to an open position, and cam means operatively mounted between said valvular means and said operating member for controlling the effective movement of said operating member with respect to said valvular 25 means, and thus for regulating the fluid flow.
4. In a filler spout, the combination of a valvular means disposed therein for controlling fluid flow therethrough, said valvular means having a stem extending therefrom, an operating lever mounted on the spout and cooperating with the end of said stem, means for abutting with and 30 moving said lever to a valve-opening position, and means positioned between said operating lever and said stem for varying the effective travel of said moving means with respect to said valve stem.
5. In a filler spout, the combination of a valvular means disposed therein for controlling fluid flow therethrough, said valvular means having a stem extending therefrom, an operating lever pivotally mounted on the spout for cooperating with the end of said valve stem, and means disposed between said operating lever and the end 35 of said valve stem for controlling the effective travel of said lever with respect to said valve stem, and means for moving said lever to a valve-opening position.
6. In a filler spout, the combination of a valvular means disposed therein for controlling fluid flow therethrough, said valvular means having a stem extending therefrom, an operating lever pivotally mounted on the spout, a fluid-flow-control-cam pivotally mounted on said lever and 40 abutting with the end of the valve stem, and means cooperating with said lever for moving it to a valve-opening position.
7. In a filler spout, the combination of a valvular means disposed therein for limiting and controlling fluid flow therethrough, an operating 45

lever pivotally mounted on the filler spout and having a portion cooperating with said valvular means, means raising said operating lever for opening said valvular means, means pivotally mounted on the spout and cooperating with said 5 raising means for holding it in a raised position, hand operable means mounted on the spout and having a portion for abutting said holding means, said last-mentioned means being adapted to operate said holding means to release said 10 raising means.

8. In a filler spout, the combination of a valvular means disposed therein for limiting and controlling fluid flow therethrough, said valvular means having an extending stem, an operating 15 means pivotally mounted on the spout and having a portion cooperating with said stem for moving said valvular means to an open position, means for holding said operating means in a raised position, means for latching said holding 20 means, and means at one end pivotally mounted on the spout for releasing said latch means.

9. In a filler spout, the combination of a valvular means disposed therein for limiting and controlling fluid flow therethrough, cooperating 25 levers for maintaining said valve in an open position, at least two of said levers being pivotally mounted at one end on the spout, another of said levers being connected to one of said two levers and being pivotally mounted on 30 the spout, and means for operating said levers and for releasing said valvular means.

10. In a filler spout, the combination of a valvular means disposed therein for controlling fluid flow therethrough, said valvular means 35 having an extending stem, an operating lever pivoted to said spout for cooperating with said stem, a controlling means cooperating with said operating lever and with said stem for controlling the effective travel of said operating lever 40 with respect to said stem, means for moving said operating lever about its pivot point to a valve-opening position, and a system for holding said last-mentioned means in a valve-opening position and for releasing said means when the fluid 45 in a container being filled has reached the desired height.

11. In a filler spout, the combination of a valvular means disposed therein for controlling fluid flow therethrough, said valvular means including 50 means for resiliently holding it in a closed position, an operating lever pivotally positioned on the spout, a cam pivotally mounted on a portion of said operating lever, said cam abutting said valve stem and having one face 55 larger than another face for varying the effective travel of said operating lever with respect to said valve stem, and thus controlling the fluid flow through said valve, and means for moving said operating lever to a valve-opening 60 position, said cam being curved continuously from a lower to an upper face, so that it may be rotated about its pivot point when the said lever has moved the valve to an open position.

12. In a filler spout, the combination of a 65 resiliently positioned valvular means disposed therein for limiting and controlling fluid flow therethrough, said valvular means having an extending stem, an operating lever pivotally mounted on said spout and having a portion 70 cooperating with the extending end of said valve stem, a cam pivotally mounted on said spout and having a face cooperating with a portion of said operating lever for moving it to a valve-opening position, a catch lever pivot- 75

ally mounted on said spout and having a portion for cooperating with said cam for holding said cam in a valve-opening position, a lever pivotally mounted on said spout and pivotally connected to said catch lever, and a trip mechanism including a dog adapted to contact said catch lever and to move said catch lever about its pivot point for releasing said cam.

13. In a filler spout, the combination of valvular means disposed therein for limiting and controlling fluid flow therethrough, said valvular means having an extending stem, an operating lever pivotally mounted on the spout and having a portion cooperating with said stem, a second lever pivotally mounted on the spout, means pivotally mounted on the spout and cooperating with said operating lever and said second lever for holding said valvular means in an open position, a third lever at one end pivotally mounted on the spout and being connected

adjacent another end to said second lever, a fluid sensitive float means disposed within said spout and connected to said third lever for operating said third lever and releasing said valve, and means pivotally mounted on the spout and adapted to cooperate with said second lever for independently releasing said valvular means.

14. In a filler spout, the combination of valvular means disposed therein for controlling fluid flow therethrough, an operating member for moving said valvular means to an open position, and means mounted on the spout for controlling the movement of said operating member, said last mentioned means being movable to vary the amount of fluid flow while said valvular means is in an open position, said means being operable from outside of the spout, so that the movement of said operating member may be controlled thereby for each operation thereof.

WALTER T. ETZEL. 20
